UNITED STATES PATENT OFFICE.

BLAINE H. HARRIS, OF ST. PAUL, MINNESOTA, ASSIGNOR TO BROWN AND BIGELOW,
OF ST. PAUL, MINNESOTA, A CORPORATION OF MINNESOTA.

METHOD OF MAKING BOTTLE-CAP LIFTERS.

Application filed November 2, 1925. Serial No. 66,265.

My invention relates to a method of making bottle cap lifters wherein it is desired to provide a simple lifter having a double function for operation, so as to increase the utility of the same.

A feature of my invention resides in method of forming the bottle cap lifter in a manner so that when it is finished it includes a sharp, needle like point, which may 10 be used for piercing and lifting the paper cap of a milk bottle or other similar caps.

My method consists in a simple die cut article made of sheet material, having a thickness of the desired nature so as to provide the necessary rigidity and firmness to 15 the parts to permit them to operate effectively.

It is a feature of the invention to include a hook portion formed in conjunction with 20 the piercing point whereby metal caps can be easily and readily lifted from bottles to open the same. The position of the lifting hook is such that the width of the lifter is used to advantage to stiffen and form rigidity and strength to the cap lifter.

My method includes means for dispensing with the sharp burr formed in cutting the same out of sheet material, so that the edges 25 of the lifter are smooth about the entire outline of the same by cutting away one side of the end of the same. I form a piercing point of a very sharp nature. This construction dispenses with the heretofore detrimental feature of losing the sharp point 35 which constitutes the piercing end of the lifter when the same was tumbled to polish and smooth the edge of the lifter in taking off the burr which is prevalent in all die cut articles formed from sheet material, such 40 as my device.

In the drawings forming part of this specification:

Figure 1 is a side view of my lifter as it 45 would appear in the first formation of blanking the same from sheet material.

Figure 2 is a side view of the finished cap lifter.

Figure 3 is a section on the line 3-3 of

Figure 1.

Figure 4 is a section on the line 4-4 of 50 Figure 2.

Figure 5 is a side or edge view of my lifter.

In the drawings the lifter A is formed from sheet metal and is blanked out with 55 the configuration and shape as illustrated in Figure 1. This is the first operation in the making of my lifter A.

One end of the lifter with a round edge 10 is formed with a hole 11 in the center by 60 which the lifter can be hung up on a nail when it is not desired for use.

The end 12 of the lifter A opposite to the end 10 is formed with a lifting hook 13 having an upwardly extending pointed edge 14 65 and a recess 15 formed in the body 16 between the hooks 13 and the end portion 12.

Extending forwardly from the hook 14 I provide the end 13 which is cut away on the inclined angle 17 and forming a shoulder 18 70 adjacent the inclined edge 17.

After the lifter A is blanked out as illustrated in Figure 1 it is then placed in a tumbling machine with many other of these lifters A and with a suitable tumbling material is tumbled about in a manner so as to remove the sharp burr edge 19 which extends about the entire edge of the lifter A 75 when it is first blanked out as illustrated in Figure 1.

After the lifters A have been tumbled sufficiently this burr 19 is entirely removed so as to form a rounded smooth edge such as 20 about the entire lifter A. This provides a lifter which will not injure the hand and 80 can be used as a household utility without cutting the hand of the operator, even though considerable pressure is exerted against the handle portion of the lifter A. The end 10 constitutes the lever or handle end of the 90 lever A.

After the lifters A have been tumbled sufficiently to remove the burr 19 the portion 22 is cut away along the dotted lines 23 so 95 as to provide an inclined angular edge 24 and a shoulder 25, which edge 24 and shoulder 25 are similar to the edge 17 and shoulder 18, in the first blanking operation formed in the end 12. This operation, cutting away the portion 22, provides a sharp needle like point 26 which inclines in the direction of draw of the cutting die so that the point 100

26 is drawn out to a sharp needle like point.

The shoulder 28 is formed projecting forward from the hook 13 which is adapted to rest against the top of a metal cap when the hook point 14 engages the cap edge to lift the same. This provides the prying action which is necessary in the lifting of a bottle cap of this nature.

Thus the method of making my bottle cap lifter constitutes the means of blanking out in the desired formation the lifter A as illustrated in Figure 1, and then in tumbling these lifters to remove the sharper edge 19 after which the portion 22 is cut away to provide the piercing point 26 of a very sharp, effective nature as is desired. Heretofore these articles have been manufactured and tumbled after the complete die cut formation. In my method the last operation is the cutting away of the portion 22 which leaves a sharp piercing point 26 inclined to one side of the lifter A in a manner so that a needle like point is drawn out on the finished lifter. The lifters are then ready to be used and are provided with such a design as would be most practical in use.

The drawings illustrate a particular formation of my lifter but I desire to have it understood that this is only suggestive as a means of carrying out my invention and that

the method employed is such that it may be applied to other means and forms within the scope of the following claims.

I claim:

1. The method of making bottle cap lifters consisting in blanking from sheet material the partial formation of the lifter, then tumbling the lifters to remove the die burr about the same, and then cutting the lifter to form a sharp piercing end. 35 40

2. The method of making cap lifters, consisting in partially blanking out the formation of the lifter from sheet metal, then polishing off the die burr about the edge of the same and then cutting the lifter to form a sharp needle like end on said lifter. 45

3. The method of making lifters consisting in dieing out from sheet material the body of the lifter, then polishing off the die burr about the same, and then notching the lifter in a manner to form a sharp needle like point with a piercing end thereon. 50

4. The method of making lifters consisting in dieing out from sheet material the body of the lifter with its complete formation excepting as to the piercing point, and then polishing off the die burr and removing a portion of the lifter to form a sharp piercing point. 55

BLAINE H. HARRIS.
